UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

CONVEYING APPARATUS.

Application filed January 18, 1919, Serial No. 271,838. Renewed July 20, 1923.

To all whom it may concern:

Be it known that I, NILS D. LEVIN, a citizen of the United States, residing at Columbus, in the county of Franklin and State of Ohio, have invented certain new and useful Improvements in Conveying Apparatus, of which the following is a specification, reference being had therein to the accompanying drawing.

10 The present invention relates to certain new and useful improvements in conveying apparatus adapted to transfer loose material from the floor of a mine to the pit cars by which it may be transported from the mine.

When the vein from which coal is to be mined is extremely thin it is customary, if geological conditions will permit, to form roadways of sufficient height for the convenient passage of the miners, and for the haulage of the pit cars by which the coal is transported from the mine, by taking up material from the underlying stratum. It is undesirable, because of the increased cost of mining, to extend these roadways into the rooms where the principal mining operations are performed, and conveyors of various types have been proposed to transfer loose material from the ever receding working face to pit cars standing upon the tracks in the entries.

My present invention relates particularly to conveying apparatus, adapted to use under conditions such as are above described, comprising an endless cable arranged to travel around suitably positioned guide sheaves, and to propel conveniently attached conveying scrapers whereby the broken down coal may be gathered from the floor of the mine adjacent the working face and deposited in pit cars conveniently positioned upon the tracks in the mine entries.

One object of my invention is to provide, in an apparatus of the class described, improved mechanism whereby the endless cable may be propelled and by which more or less of its length may be held in reserve to permit the convenient extension of the conveyor as the working face recedes from the

50 entry.

A further object is to provide improved conveying scrapers adapted to gather and transport material as they move forwardly towards the mine entry and to avoid such material as they move rearwardly towards

the position from which it is desired to gather a load.

A further object is to provide improved automatically disengaging means for attaching the conveying scrapers to the propelling cable.

These and other objects are fully set forth in the following specification and illustrated in the accompanying drawings of which—

Fig. 1 is a plan view of a portion of a coal mine equipped with my improved conveying apparatus.

Fig. 2 is a vertical section through said coal mine showing an elevation of the apparatus illustrated in Fig. 1.

Fig. 3 is a plan view, on an enlarged scale, of the propelling mechanism shown in Figs. 1 and 2.

Fig. 4 is a side elevation, partly in section, of the devices illustrated in Fig. 3.

Fig. 5 is a plan view, on an enlarged scale, of one of my improved conveying scrapers.

Fig. 6 is a side elevation of the scraper illustrated in Fig. 5.

Fig. 7 is a rear end elevation of the scraper illustrated in Figs. 5 and 6.

Fig. 8 is an end view of one of the cable gripping clamps by which the scrapers are connected with the propelling cable.

Fig. 9 is a plan view of the clamp illustrated in Fig. 8.

Like numerals refer to similar parts in the several figures.

In Figs. 1 and 2 of the drawings I have illustrated a portion of a mine working wherein coal is being recovered, from a very thin vein, by the use of my improved conveying apparatus.

In the drawings the numeral 1 indicates an entry provided with the customary tracks 2 along which the pit car 3 may travel to transport the coal from the mine. In order to procure sufficient head room in the entry for the convenient passage of the miners, and for the haulage of the pit cars, the underlying stratum has been taken up to such a depth that the upper edge 4 of the side wall of the pit car 3 is approximately level with the bottom of the coal vein. The numeral 5 indicates one of the rooms in which the principal mining operations are conducted, 6 is the relatively narrow room neck by which the room communicates with the entry, and 7 is the working face from

which the coal is being mined. Suitably positioned near the working face are adjustable jack posts 8, 9 and 10 of a type commonly used in mine practice, having 5 roof engaging members 11 adapted to be forced into contact with the roof by the hand wheel nuts 12. Attached to or mounted upon the jack posts 8, 9 and 10 in any preferred manner are sheave wheels 10 13, 14 and 15 adapted to guide the longitudinal moving endless haulage cable 16. 17, 18, 19 and 20 are conveying scrapers each of which is provided with a towing line 21 arranged to be connected to the 15 haulage cable 16 by suitable cable gripping devices 22. The cable 16 extends through the room neck 6 and across the entry 1 to the propelling mechanism 23 positioned in a convenient recess 24 of the mine wall. 20 The propelling mechanism 23 comprises an elongated base frame 25 near the opposite ends of which are mounted two upwardly extending substantially vertical shafts 26 and 27. The vertical shaft 26 25 is rigidly fixed to the base frame 25 and supports a plurality of similar, freely rotatable sheave wheels 28 each of which is provided with a circumferential groove 29 adapted to engage the cable 16. The vertical shaft 27 is journaled in suitable bearings 30 and 31 of the base frame, and to this shaft is fixed a drum wheel 32 upon which is formed a plurality of circumferential grooves 33 corresponding to the grooves 29 30 in the sheave wheels 28, and adapted to engage the cable 16. To the shaft 27 is secured a worm wheel 34 which is engaged by a worm 35 mounted upon a horizontal worm shaft 36. The worm shaft 36 is journaled in suitable bearings 37 and 38 of the base frame, and is connected with a suitable motor 39 by which the cable 16 is actuated. In the drawings I have shown, for purposes of illustration, an electric motor which may 40 be actuated from any convenient source of electric power, but any preferred type of motor may be used which is suitable to the conditions under which the apparatus is to be operated. An idler sheave 40 mounted 45 upon the base frame 25 for rotation in a horizontal plane receives the cable 16 as it approaches the driving mechanism. From the idler sheave 40 the cable 16 passes around a tensioning idler 41 and to the 50 lowermost groove 33 of the drum wheel 32. The tensioning idler 41 is supported upon a base casting 42 which is slidable in guide ways 43 of the base casting, and which is connected with a counterweight 44 by a cable 55 arranged upon suitable pulley sheaves 46, 47 and 48 in the manner well understood by those skilled in the art. From the lowermost groove 33 of the drum wheel 32 the cable 16 passes around the lowermost idler sheave 28 and from that to the second groove 60 of the drum wheel and so on until the desired amount of reserve cable is wrapped upon the sheaves of the driving mechanism. From the last groove of the drum wheel 32 the return strand of the cable 16 passes 70 across the entry and into the mine room 5. In the early stages of the development of the mine room, while the working face is near the entry, as indicated by the dotted lines at 49 the larger part of the cable 16 will 75 be held in reserve upon the sheave wheels 28 and 32 of the driving mechanism. The number of grooves available for cable storage, the size of the sheave, and the distance apart of the shafts 26 and 27 will depend 80 upon the degree of extensibility desired in the conveyer. As the working face recedes the jack posts 8, 9 and 10 are progressively moved forward, and as they advance loops 85 of the cable 16 are disengaged from the sheaves of the propelling mechanism to permit the extension of the conveyer to maintain working relations with the ever receding coal face. 90 Each of the conveying scrapers is formed of an elongated rectilinear steel plate 50, bent along its transverse center line in the form of a letter V, and adapted to rest upon one of its longer edges directly upon the mine floor. At the forward end of the 95 scraper the ends of the plate 50 are braced apart by a transverse bar 51 which is positioned sufficiently high to permit the free passage of material beneath it into the scraper. At the forward end of the scraper the lower corners 52 of the plate 50 are rounded off to facilitate forward movement of the scraper over the irregularities of the mine floor, and at its rear end, that is to say, at the point of the V, the lower corner 100 53 is similarly rounded by bending the lower edge of the plate 50 forwardly. This forward bending of the plate 50 also serves to engage the material within the scraper to hold down the rear end of the scraper as it moves forwardly. An upstanding fork 105 54 attached to the rear end of the scraper is adapted to engage the towing line 21 when it is desired to move the scraper rearwardly. 110 The cable gripping device 22 consists of a body portion 55 which in service preferably lies in a horizontal position immediately below the cable 16. Upon the body portion 55 is formed an upwardly extending flange 56 having a cable seat 57 conforming approximately to the curvature of the surface of the propelling cable 16. Positioned in opposition to the flange 56 is a cam 58 which is adapted to hold the cable in forced engagement with the cable seat 57. The cam 58 is formed integral with a pivot pin 59 which extends through an aperture in the body portion 55. To the pivot pin 115 59 is attached a lever 60, and to the outer 120 125 130

end of this lever is connected the towing line 21. The proportion of parts is such that the stress upon the towing line tends to rotate the lever 60 to force the cam 58 against the cable 16, and when the cam is in such forced engagement with the cable the point of attachment of the towing line 21 to the lever 60 will lie in the vertical plane of the cable 16 and the direction of the line 10 of draft will tend to hold the body portion 55 in the desired horizontal position. An extension 61 of the cam 58 projects beyond the edges of the body portion 55 and serves as a handle by which the cam may be rotated 15 for the engagement and disengagement of the cable.

After the coal has been broken down from the working face in the usual manner, a sufficient number of turns of the cable 16 are disengaged from the sheaves 28 and 32 20 of the driving mechanism to permit the desired extension of the conveyer. The jack posts 8 and 9 are adjusted, one at each side of the room 5, in such position that the 25 transversely moving strand 62 of the cable 16 will be held substantially parallel to the working face in proximity with the pile of loose material upon the floor of the mine. The jack post 10 is then adjusted in such 30 position that the inwardly moving strand 63 of the cable 16 will be sufficiently removed from the outwardly moving strand 64 to prevent interference of the inwardly and outwardly moving scrapers, and at the 35 same time take up such portions of the slack of the cable that the tensioning sheave 41 will properly function within the limits of its movement. The diameter and width of face of the guide sheaves 13, 14 and 15 40 are such that these wheels are capable not only of changing the direction of the cable 16 but also of guiding the scrapers attached to said cable. After the jacks 8, 9 and 10 are properly adjusted a scraper is placed in 45 suitable relation with the material to be gathered, as shown at 17 in Fig. 1, and the grip adjusted to connect its towing line to the transversely moving strand 62 of the cable. This scraper will then be dragged 50 across the working face 7 gathering loose material between its converging sides and conveying such material around the sheave 14 as indicated at 18 in Fig. 1 and towards the entry.

55 A steel apron 65 is provided to bridge the gap between the floor of the mine room and the side 4 of the pit car 3 and over this steel apron the scrapers are drawn, as indicated at 19 in Fig. 1, to discharge the material into the pit car 3. To avoid the necessity of lifting the scraper out of the pit car after it has discharged this material, the cable grip 22 is released from the cable 16 as soon as the forward edge of the scraper 60 has reached the forward edge of the

apron 65. The towing line 21 is then placed in engagement with the fork 54 and the grip 22 attached to the inwardly moving strand 63 of the cable. The scraper is then drawn rearwardly, as indicated at 20 in Fig. 1, leaving a portion of its load upon the apron to be pushed into the pit car by the material in the next advancing scraper. To insure the proper disengagement of the grip 22 I have provided two upstanding 70 wings 66 formed upon the base frame casting 25 of the propelling mechanism one at either side of the outwardly moving strand 64 of the cable. These wings 66 diverge rearwardly of the cable and are so positioned that they engage the flange 56 and the cam extension 61 of the cable grip in such manner as to force the cam 58 in the cable releasing direction permitting the grip to fall away from the cable. The length of 80 the towing line 21 is so adjusted as to insure the stoppage of the scraper 20 upon the apron 65. The grip 22 may immediately be attached to the inwardly moving strand 63 of the cable and the tow line 21 engaged with the fork 54 to cause the return of the empty scraper to the working face. The guide sheaves 15 and 13 are of such proportion that the scrapers will be guided by them to follow the cable to the position 17 85 to take a new load, and the operation may be repeated ad libitum.

What I claim is:

1. In an apparatus of the class described for delivering material at a predetermined point, the combination of the endless cable traveling continuously in one direction, a scoop receptacle propelled by the cable, draft devices detachably fastened to the cable and permanently connected to the said receptacle, and means located adjacent the roller and the sheaves for automatically releasing said fastening devices from the cable at a point predetermined relatively to the roller.

2. In an apparatus of the class described for delivering material at a predetermined point, the combination of an endless cable traveling continuously in one direction, a scoop receptacle propelled by the cable and traveling longitudinally toward said delivery point and then, without reversal, traveling longitudinally away from said point, a flexible draft device adapted to be optionally connected to the said cable and to be automatically disengaged therefrom and arranged to exert draft at the forward end of the receptacle when moving toward said point and to exert draft at the opposite end thereof when moving in the opposite direction.

3. In apparatus of the class described for delivering material at a predetermined point, the combination of an endless cable traveling continuously in one direction, a

scoop receptacle propelled by the cable and traveling longitudinally toward said delivery point and then, without reversal, traveling longitudinally away from said point, a flexible draft device adapted to be optionally connected to the said cable and to be disengaged therefrom and arranged to exert draft at the forward end of the receptacle when moving toward said point and to exert draft at the opposite end thereof when moving in the opposite direction. In testimony whereof, I affix my signature, in presence of two witnesses.

NILS D. LEVIN.
